CLAIM

The ornamental design for portable audio player, as shown and described.

DESCRIPTION

FIG. 1 is an overall view of the portable audio player claimed in this application ("claimed design");
FIG. 2 is a front view of the claimed design;
FIG. 3 is a rear view of the claimed design;
FIG. 4 is a left side view of the claimed design;
FIG. 5 is a right side view of the claimed design;
FIG. 6 is a top view of the claimed design; and,
FIG. 7 is a bottom view of the claimed design.
The broken lines shown in the figure drawings represent unclaimed portions of the portable audio player and form no part of the claimed design.
